US00D632326S

(12) **United States Design Patent**
Hou

(10) **Patent No.:** **US D632,326 S**
(45) **Date of Patent:** **** Feb. 8, 2011**

(54) **MICRO PROJECTOR**

(75) Inventor: **Hsiang-Fei Hou**, Tu-Cheng (TW)

(73) Assignee: **Cheng Uei Precision Industry Co., Ltd.**, Tu-Cheng, Taipei Hsien (TW)

(**) Term: **14 Years**

(21) Appl. No.: **29/362,902**

(22) Filed: **Jun. 1, 2010**

(51) **LOC (9) Cl.** **16-02**

(52) **U.S. Cl.** **D16/229; D16/230**

(58) **Field of Classification Search** D16/205–206,
